(57) **CLAIM**

The ornamental design for a lid for container, as shown and described.

DESCRIPTION

FIG. 1 is a top perspective view of a lid for container incorporating our ornamental design;
FIG. 2 is a front view of the lid for container incorporating our ornamental design;
FIG. 3 is a rear view of the lid for container incorporating our ornamental design;
FIG. 4 is a side view of the lid for container incorporating our ornamental design;
FIG. 5 is an opposite side view of the lid for container incorporating our ornamental design;
FIG. 6 is a top view of the lid for container incorporating our ornamental design;
FIG. 7 is a top perspective view of a lid for container incorporating an alternative embodiment of our ornamental design;
FIG. 8 is a front view of the lid for container of FIG. 7;
FIG. 9 is a rear view of the lid for container of FIG. 7;
FIG. 10 is a side view of the lid for container of FIG. 7;
FIG. 11 is an opposite side view of the lid for container of FIG. 7;
FIG. 12 is a top view of the lid for container of FIG. 7;
FIG. 13 is a top perspective view of the lid for container incorporating an alternative embodiment of our ornamental design;
FIG. 14 is a front view of the lid for container of FIG. 13;
FIG. 15 is a rear view of the lid for container of FIG. 13;
FIG. 16 is a side view of the lid for container of FIG. 13;
FIG. 17 is an opposite side view of the lid for container of FIG. 13; and,
FIG. 18 is a top view of the lid for container of FIG. 13.
The broken line showing of a cap and vent holes is included for the purpose of illustrating environmental structure and forms no part of the claimed design.
